UNITED STATES PATENT OFFICE.

HOWARD S. KIMMEL, OF TIFFIN, OHIO.

TRAIN-PIPE COUPLING.

1,154,028.

Specification of Letters Patent. Patented Sept. 21, 1915.

Application filed October 10, 1914. Serial No. 866,122.

To all whom it may concern:

Be it known that I, HOWARD S. KIMMEL, a citizen of the United States, residing at Tiffin, in the county of Seneca and State of Ohio, have invented certain new and useful improvements in Train-Pipe Couplings; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in automatic air brake apparatus, one of the objects in view being to produce means whereby the valve in the air pipe is automatically opened when two cars are coupled together.

The invention relates further to the provision of means whereby, when the valve is automatically opened, it will be held locked in such relation until released by the uncoupling of the car couplers.

The invention consists further in the provision of means whereby the valves may be automatically locked closed when the car coupler is uncoupled, the apparatus being so constructed that, in the event of the cars being accidentally uncoupled, the valve will remain in an open locked relation, thus insuring the application of the air brakes and thereby avoiding accidents.

The invention relates further to various details of construction, combinations and arrangements of parts which will be herein-after fully described, shown in the accompanying drawings and then specifically defined in the appended claims.

My invention is illustrated in the accompanying drawings in which:

Figure 1 is a top plan view showing the couplers about to be connected. Fig. 2 is a similar view showing the coupler heads connected together. Fig. 3 is a sectional view on line 3-3 of Fig. 1. Fig. 4 is a sectional view on line 4-4 of Fig. 1. Fig. 5 is a sectional view on line 5-5 of Fig. 1. Fig. 6 is a sectional view on line 6-6 of Fig. 1. Fig. 7 is a sectional view on line 7-7 of Fig. 1. Fig. 8 is a sectional view on line 8-8 of

Fig. 1. Fig. 9 is a sectional view on line 9-9 of Fig. 1. Fig. 10 is a detail sectional view on line 10-10 of Fig. 1. Fig. 11 is a plan view of a detail of a latch. Fig. 12 is a sectional view on line 12-12 of Fig. 11. Fig. 13 is an enlarged detail view of a catch. Fig. 14 is a sectional view on line 14-14 of Fig. 13 looking in the direction of the arrow, and Fig. 15 is an enlarged detail perspective view of a releasing member.

Reference now being had to the details of the drawings by numeral, 1 designates a metallic box adapted to contain the operative features of the apparatus and which is fastened to the under surface of the boxing of a car coupler in any suitable manner. The inner faces of the side walls of the boxing 1 are provided with recesses, and 5 and 6 designate two grooved tracks formed in the lower marginal edges of said recesses; and 7 designate rack bars having shank portions 8 which are provided with elongated openings therein and forming an upper and a lower extension and at the forward ends of said openings are buffer members 8*. Ball rollers 9 are journaled in sockets 10 which are fastened at any suitable location under the rack bar and the shank portion thereof, 80 said balls being adapted to travel in said grooved tracks.

11 designates a fluid pressure pipe, of the usual construction upon air brake mechanism, and provided with a valve 12, the stem 13 of which projects above the valve casing and through an aperture in a plate or table 14 which is adjustably mounted upon the threaded bars 15 which pass through registering apertures in the bottom 90 of the boxing 1 and an integral plate 16 secured to the opposite upper edges of the boxing 1. Nuts 17 mounted upon the threaded rods serve as means for holding the plate 14 in different adjusted positions.

A cog wheel 19 has an angular outlined aperture adapted to fit a correspondingly angular portion of the stem of said valve is supported by said table, the teeth of the cog wheel being in mesh with one of the rack bars, as shown clearly in the drawings. A second cog wheel, designated by numeral 20, is loosely journaled upon a vertical shaft or pin 21 passing through registering apertures

in the plates 14, 16 and the bottom of the boxing 1 and meshes with the teeth of the gear 19 and also with the teeth of the rack bar opposite the one engaged by said wheel 19, the purpose of said loosely mounted gear wheel 20 being auxiliary and assisting in the rotary movement of the gear wheel 19 and the valve connected therewith.

A movable carriage, designated by numeral 23, is provided with lateral extensions upon which are journaled flanged wheels 24, four of which on each side of the carriage are adapted to travel upon the upper surfaces of the extensions 8 of said 15 rack bars, while two upon each side are adapted to engage the under surface of the top walls of the recesses in the side and to aid the carriage as it moves back and forth for a purpose which will be presently described. Said carriage has registering openings centrally formed therein for the reception of the cylinder 25, one end 26 of which has an opening 27 for the reception of the pipe 28, which is connected to the train pipe 25 11. Said boxing 1 is provided with a transverse partition 29 which is apertured for the reception of said cylinder 25 and against which one end of the spring 30 bears, the other end of which bears against the cross-piece 31 at the forward end of the carriage, the purpose of said spring being to cause the carriage to be driven forward after being released by locking mechanism which will be presently described.

35 A yoke, designated by numeral 32, is fixed to the forward end of the pipe 28 and rods 33 are fastened at their forward ends, one to each arm of said yoke, and extending back one over and the other under the carriage, being guided through apertures 34 in said partition 29 and their rear ends are bent at right angles at 35 and are fastened to the sections 36 of a ring which are fastened to the pipe 28. Said rods serve to reinforce 40 said yoke through which the forward end of the pipe 28 projects and to which the hose 37 is connected. A fluid pressure coupler 38 has arms 39 which are pivotally mounted upon the pins 40 which are carried in registering apertures in the lugs 41 which are integral with a coupler guiding bar 42, which latter is provided with lugs 43, apertured for the reception of the pivotal pins 44, one of which is mounted in each arm 32 45 of said yoke. A plate 45 is fastened to the upper surface of the guide bar 42, preferably at the center, and projects over the upper arm 32 and is provided with an aperture for the reception of the pivotal pin 44, 50 thus serving to further reinforce and hold the bar 42. In order to prevent an axial turning movement of the coupler head, rods 46, having heads 47, are mounted to have a longitudinal sliding play in the tubes 48, 55 which pass longitudinally through the car-

riage and are provided with circumferential threads on which adjusting nuts 48^x are mounted and adapted to engage portions of the carriage to securely reinforce and hold the same rigid. The heads 47 are slotted 70 and carry anti-friction rollers 50 which are adapted to have a play in the elongated curved slots 51 formed in part of the guiding bar 42 and which will permit the latter to turn freely without giving any lateral 75 movement to the guide rods. The ends of the guide bar 42 are pivotally connected to the members 52, each of which has a right threaded screw 53 fastened thereto, and 54 are turn buckles, one being connected to each 80 right threaded screw 53 at one end and its other end left threaded screws 55 formed on the ends of the longitudinally movable rods 56. Each rod 56 passes through an aperture 57 in the end of a tubular shell 58 85 which in turn telescopes within a tubular shell 59 provided with a head 60 at one end which is pivotally mounted upon a pin 61 carried by the projections 62 which are adapted to be fastened to the truck bolster 90 of a car at equal distances from the center thereof. Each of said rods 56 has a plunger 63 at its inner end and a spring 64 is interposed between the plunger and the apertured head to the shell 58. Each of said tubes 58 has a collar or flange 65 projecting therefrom a slight distance from its inner end and against which one end of a coiled spring 66 bears, the other end of the spring bearing against the head 60. 100

By the provision of the spring-pressed connections intermediate the guide bar 42 and the truck bar of a car, it will be noted that the coupler head 38 will be turned with the axle as the car passes about curves in 105 the tracks and the spring connections described will permit the coupler head to be drawn forward or pushed backward toward the car under varying conditions and at the same time serve as proper guiding means 110 for the coupler head.

The yoke 32 has a forwardly projecting part 71, having an aperture 72 therein for the reception of an open-ended cylindrical shell 73 movable therethrough, and said shell is provided with flanges 75 at its opposite ends, one of which is positioned below said projections and tends to limit the movement of the shell in one direction and the other flange serves as a bearing for the coiled spring 76 which is interposed between the same and the upper surface of said extension, the purpose of said spring 76 being to normally hold the cylindrical shell 73 at 115 its farthest upper limit. A plunger rod 79 is mounted within said cylindrical shell and has a plunger 80 at its lower end intermediate which and the inner edge of the collar at the upper edge of the cylindrical shell a spring 81 is mounted. Said plunger rod is 120 125 130

provided with an eye 82 at its upper end which is connected to a rod 83 upon the under surface of the coupler head 38. The purpose of said plunger rod is to allow the 5 coupler head to rise up independent of the cylindrical shell in the event of it being necessary to raise the coupler head to connect with another coupler at a higher elevation than horizontal, the coiled spring 81 tending 10 to return the coupler head to its normal position after being uncoupled. In the event of the coupler being connected to a corresponding coupler head when the latter is in a lower plane than the normal position of 15 the coupler described, the coiled spring upon said projection would allow both the cylindrical shell and the plunger rod within to be depressed, the parts being returned to their normal positions by the springs after 20 the heads are uncoupled.

Said rack bars have openings 85 extending through the same, portions of said openings being reduced as at 86 forming shoulders against one edge of which one edge of a 25 spring 87 bears, the other end bearing against the head of a bumper or buffer 88 mounted upon a rod 84, said buffers being positioned in the path of the carriage and against which the latter is adapted to contact when moving toward the valve to be 30 opened when the cars are coupled. A bur 89 is mounted upon the threaded end of each of said plunger rods and is adapted to contact with another shoulder 90 formed in the 35 opening through the rack bar and serves as a means, when the bur comes in contact therewith, to limit the outer throw of the plunger.

The lower extensions of the rack bars are 40 provided with elongated slots 93, and 94 designates pivotal pins mounted in the walls of said slots and upon which the locking levers 96 are pivotally mounted, which are adapted to lock the valve open. Each of 45 said locking levers is provided with an integral hook 97 upon its under edge intermediate the pivotal point of the lever and its inner end and which is adapted to engage a catch 98 which is pivotally mounted upon 50 a pin 99 which is carried by a casing 100, adjustably mounted in a recess in the concaved track. A spring 101 is fastened at one end to the casing and its other end bears against said catch and tends to normally 55 hold the same in position to be engaged by the hook upon the locking lever.

The means for adjusting the casing carrying the catch consists of a threaded shaft 102 mounted in apertured lugs 103 projecting from the shell, and a nut 104 is mounted in the threaded end of each shaft and rotates in a recess 105, holding the same stationary as it rotates, thus imparting a longitudinally adjustable movement to the shafts. A 60 second set of locking levers, each designated

by numeral 106, is pivotally mounted upon a pin 107 in a slot 108 formed in the forward ends of the under projections of the rack bars and a hook 109 is formed upon each locking lever 106 and adapted to engage a spring-pressed catch 110 mounted in an adjustable casing 111 in a similar manner as before described with reference to the other locking members and which locking levers 106 are provided for the purpose of holding the rack bars against longitudinal movement and which in turn will hold the air valves closed. 70 75

The shells, designated by numeral 112, are mounted one upon each tube 48 and a portion of the interior of each shell 112 and its rear end is threaded to engage the threads of the tubular shell upon which it is mounted, thus affording means for adjustment. The forward ends of the shells 80 85 112 serve, in coöperation with the upper forked ends of the arms 113, of the forked lever 114, to hold the carriage in the position into which it is moved in the act of being driven rearward to cause the valve in 90 the air pipe to be thrown open and also to hold the carriage in such a position that the hooked ends of the levers 96 will be held in engagement with the spring-pressed hooks beneath, thus securely locking the air valve 95 open. It will be noted upon reference to the drawings that the carriage may have, however, a further forward movement independent of the said locking means without in any way causing the valve to close 100 and which movement might be caused by the play of the car couplers. Said forked lever 114 is pivotally mounted upon the shaft 115 which is mounted in lugs or projections on the under side of the box 1, and a spring 116 105 is fastened to the bottom of the boxing 1 and bears against said lever and normally holds the forked arms at their farthest upper limit. Said lever has a shank portion 117 which projects in advance of the boxing 110 and has its end bent laterally to avoid interference with a similar lever upon an adjacent car, and underneath said shank portion is positioned a bail-shaped member 119, the arms of which are pivotally connected to 115 the boxing 1 at any suitable location. When two coupler heads are connected together, as shown in Fig. 1 of the drawings, it will be noted that the bail-shaped member will be so positioned as to be raised by the ordinary 120 rocking shaft utilized upon couplers for raising coupling pins and which movement will cause the member 117 to be tilted sufficiently to throw the forked ends 113 out of the paths of the threaded shells 48. 125

The operation of my apparatus is as follows: When two coupler heads come together and pressure is applied to the same, the impact of the coupler heads coming together will cause the carriage to be moved 130

back into the boxing, putting the spring 30 under tension and, as the inner end of the carriage comes against said plungers, the latter will yield slightly to take up jar and 5 will cause longitudinal movements to be imparted to the rack bars which, through their connections with the gear wheels, will cause the valve stem of the valve in the air pipe to rotate and open the valve. When the lower 10 flanged wheels at the inner end of the carriage ride over the pivotal points of the locking levers 96 and after they roll over the pivotal points and approach the hooked ends thereof, the latter will tilt down and engage 15 said spring-pressed catches which are mounted in the recesses in the tracks, thus securely holding the rack bars in adjusted position and also locking the valve open by reason of the gear connections between the 20 valve and said rack bars. As the car commences to open the valves and the outer ends of the shells 48 pass by the forked ends of the arms upon the lever 114, said forked ends will be thrown up behind the ends of 25 the shells 48, thus locking the car against any possibility of the latter releasing the locking levers before described, in the event of the car couplers becoming broken or disconnected for any reason, excepting, of 30 course, in the event of the couplers being intentionally disconnected.

It will be noted, upon reference to the drawings, that, when the car and the rack bars are locked in the manner shown, the 35 car may have a slightly farther movement within the boxing 1 incident to the shifting of cars which might cause extra pressure to come upon the coupler head and this movement is allowed without any interference whatever with the locking mechanism. 40

When it is desired to uncouple a car, the operator by rocking the shaft to release the car coupler will cause the bail-shaped member to tilt the forked lever 114 and, as the 45 forked arms at the inner end thereof are drawn down out of the paths of shells 48, the spring 30, coöperating with the springs in the telescoping shells which are connected to the axle, will throw the carriage forward 50 and, as the under flanged wheels at the forward end of the car run over the pivotal points of the locking levers 96, their forward or outer ends will be tilted to throw the hooks out of engagement with said 55 catches and, as the flanged wheels at the outer end of the car travel over the pivotal points of the locking levers 106, the hooked ends of the latter will be thrown down into engagement with spring-actuated catches 60 mounted in recesses in the hollow tracks and thus lock the car at its farthest outer limit. As the car strikes the buffers 8^x, an outer longitudinal movement will be imparted to the rack bars and, through the

medium of their connection with the valve, 65 the latter will be closed and held in a closed locked relation, even though a limited inner thrust be imparted to the coupler head.

By the provision of the pivotal guiding lever 42, it will be noted that, when the axle 70 of the car turns incident to passing about a curve, a similar swinging movement will be imparted to the coupler head and, in the event of there being a play between the two cars coupled together by the usual car couplers, the spring-pressed rods and the telescoping tubular sections which are connected to the axle are allowed to have a play without in any way interfering with the lateral guiding movement of the coupler head. 75 80

By the provision of the extension centrally underneath the pivotal point of the guiding bar and the spring connections between the same and the coupler head, the latter may be allowed a vertical swinging movement 85 which might be necessary in order to bring the coupler opposite another coupler of similar construction upon an adjacent car, and, by the manipulation of the adjusting screws which are connected to the boxing, the latter 90 may also be given an adjustable movement for the same purpose. 95

By the provision of the spring-pressed yoke 32 mounted as shown, it will be understood that a forward pull upon the coupler head, after the car had been held in a locked position at its farthest outer throw, would allow the yoke to be drawn forward, putting the spring 32^x which bears against the same under tension and also the springs mounted 100 within the telescoping shells which are connected to the axle and, when the pull is released, the parts will be returned by the springs to their normal positions. This movement of the forked member compensates for the play which is usually taken up 105 in fluid pressure couplings by the flexible hose connections.

What I claim to be new is:

1. An automatic apparatus for regulating 110 the valves in fluid pressure train pipes comprising, in combination with the stem of a valve, a pipe, a gear wheel fixed to said stem, a movable carriage, a coupler head connected to the latter, means actuated by the movement of the latter for causing said gear wheel to rotate to open the valve, and means for holding the valve in an open position. 115

2. An automatic apparatus for regulating 120 the valves in fluid pressure train pipes comprising, in combination with the stem of a valve, a pipe, a gear wheel fixed to said stem, a movable carriage, a coupler head connected to the latter, a rack bar in mesh with the gear wheel, said rack bar forming 125 means for moving the latter in one direction to cause the valve to open, and means for locking the valve in an open position.

3. An automatic apparatus for regulating the valves in fluid pressure train pipes comprising, in combination with the stem of a valve, a pipe, a gear wheel fixed to said stem, 5 a movable carriage, a coupler head connected to the latter, a rack bar in mesh with the gear wheel, said rack bar forming means for moving the latter in one direction to cause the valve to open, and means actuated by 10 the movement of the carriage in one direction for locking the valve open.
4. An automatic apparatus for regulating the valves in fluid pressure train pipes comprising, in combination with the stem of a valve, a pipe, a gear wheel fixed to said stem, 15 a movable carriage, a coupler head connected to the latter, a rack bar in mesh with the gear wheel, said rack bar forming means for moving the carriage in one direction to cause 20 the valve to open, a tilting locking lever actuated by the movement of the carriage in one direction, and a spring-pressed catch engaged by said locking member to hold the valve in an open relation.
- 25 5. An automatic apparatus for regulating the valves in fluid pressure train pipes comprising, in combination with the stem of a valve, a pipe, a gear wheel fixed to said stem, a rack bar in mesh with the gear wheel, 30 a buffer carried by the rack bar, a spring-pressed carriage adapted to contact with said buffer and move the rack bar in one direction to open the valves, a coupler head connected to the carriage, means actuated 35 and held by the carriage for holding the valve open, and means for holding the carriage in a locking position.
6. An automatic apparatus for regulating the valves in fluid pressure train pipes comprising, in combination with the stem of a 40 valve, a pipe, intermeshing gear wheels, one of which is mounted upon the stem of said valve, rack bars in mesh with said wheels, buffers carried by the rack bars, a carriage, 45 wheels upon which the same is mounted, a spring-pressed yoke upon the carriage, a coupler head connected to said yoke, said carriage adapted to contact with said buffer members to actuate the rack bars to cause 50 the valve to be thrown open, tilting locking levers carried by the shank portions of the rack bars and positioned in the paths of the wheels of the carriage, spring-pressed 55 catches underneath the locking levers and engaged thereby to hold the valve open, means for locking the carriage while the valve is open, and means for releasing the carriage.
7. An automatic apparatus for regulating 60 the valves in fluid pressure train pipes comprising, in combination with the stem of a valve, a pipe, intermeshing gear wheels, one of which is mounted upon the stem of said valve, rack bars in mesh with said wheels,
- buffers carried by the rack bars, a carriage, 65 wheels upon which the same is mounted, a spring-pressed yoke upon the carriage, a coupler head connected to said yoke, said carriage adapted to contact with said buffer members to actuate the rack bars to cause 70 the valve to be thrown open, tilting locking levers carried by the shank portions of the rack bars and positioned in the paths of the wheels of the carriage, spring-pressed 75 catches underneath the locking levers and engaged thereby to hold the valve open, a tilting lever having arms which hold the car in a locked position when the car is coupled, means adapted to be actuated by the mechanism of a car coupler for tilting said lever 80 to allow the car to be released, and means for locking the car when at its farthest outer throw.
8. An automatic apparatus for regulating the valves in fluid pressure train pipes comprising, in combination with the stem of a valve, a pipe, intermeshing gear wheels, one of which is mounted upon the stem of said valve, rack bars in mesh with said wheels, 85 buffers carried by the rack bars, a casing with recesses in the walls thereof in which said rack bars have longitudinal play, the lower edges of said recesses being grooved forming tracks, roller bearings underneath said rack bars and movable within said 90 tracks, each rack bar having an opening in the shank portion thereof with slots in the lower edges thereof, angle levers pivotally mounted one in each of said slots, hooks upon said levers, spring-actuated catches 95 mounted in recesses in said tracks and adapted to be engaged by said hooks, a carriage, wheels upon which the same is mounted, said wheels movable within the recesses in the shank portions of the rack bars and adapted 100 to tilt the levers at one end of the carriage on the inner throw thereof to cause the valve to be locked open, and the other levers being adapted to hold the valve closed.
9. An automatic apparatus for regulating 110 the valves in fluid pressure train pipes comprising a boxing with recesses in the inner faces thereof, a train pipe valve having a stem projecting therefrom, intermeshing gear wheels, one of which is fitted to said 115 stem, an adjustable table supporting said gear wheels, rack bars movable within the recesses in the walls of the boxing, rollers underneath the rack bars, tracks formed in the bottoms of said recesses upon which said 120 rollers rest, buffers mounted within the rack bars, said rack bars having shank portions with elongated openings therein the lower walls of said openings having slots therein, a carriage having flanged wheels, the lower 125 of which is adapted to ride upon the lower marginal edges of said openings and the upper wheels engaging the upper marginal

edges of said openings, angle locking levers pivotally mounted in said slots in the bottoms of the openings, a hook projecting from each lever, spring-pressed catches mounted 5 in recesses in the tracks and engaged by said hooks, an apertured partition in said boxing, a cylinder upon the carriage movable through said partition, a spring interposed between the latter and one end of the 10 carriage, a spring-pressed pipe mounted within said cylinder and having connection with said valve, a coupler connected to the pipe, and means for locking the carriage as it is thrown to a position to open the valve.

15 10. An automatic apparatus for regulating the valves in fluid pressure train pipes comprising a boxing with recesses in the inner faces thereof, a train pipe valve having a stem projecting therefrom, intermeshing 20 gear wheels, one of which is fitted to said stem, an adjustable table supporting said gear wheels, rack bars movable within the recesses in the walls of the boxing, rollers underneath the rack bar, tracks formed in 25 the bottoms of said recesses upon which said rollers rest, buffers mounted within the rack bars, said rack bars having shank portions with elongated openings therein the lower walls of said openings having slots therein,

30 a carriage having flanged wheels, the lower of which is adapted to ride upon the lower marginal edges of said openings and the upper wheels engaging the upper marginal edges of said openings, angle locking levers 35 pivotally mounted in said slots in the bottoms of the openings, a hook projecting from each lever, spring-pressed catches mounted in recesses in the tracks and engaged by said hooks, an apertured partition in said boxing, a cylinder upon the carriage movable 40 through said partition, a spring interposed between the latter and one end of the carriage, a spring-pressed pipe mounted within said cylinder and having connection with said valve, a yoke mounted upon said pipe, a guiding bar pivotally connected to the yoke, a coupler upon the guide bar, and means attached to the guiding bar for connection with the truck bolster of a car.

45 11. An automatic apparatus for regulating the valves in fluid pressure train pipes comprising a boxing with recesses in the inner faces thereof, a train pipe valve having a stem projecting therefrom, intermeshing 50 gear wheels, one of which is fitted to said stem, an adjustable table supporting said gear wheels, rack bars movable within the recesses in the walls of the boxing, rollers underneath the rack bar, tracks formed in 55 the bottoms of said recesses upon which said rollers rest, buffers mounted within the rack bars, said rack bars having shank portions with elongated openings therein the lower walls of said openings having slots therein,

60

a carriage having flanged wheels, the lower 65 of which are adapted to ride upon the lower marginal edges of said openings and the upper wheels engaging the upper marginal edges of said openings, angle locking levers pivotally mounted in said slots in the bottoms of the openings, a hook projecting from each lever, spring-pressed catches mounted in recesses in the tracks and engaged by said hooks, an apertured partition 70 in said boxing, a cylinder upon the carriage movable through said partition, a spring interposed between the latter and one end of the carriage, a spring-pressed pipe mounted within said cylinder and having connection with said valve, a yoke mounted 75 upon said pipe, a guiding bar pivotally connected to the yoke, a coupler upon the guide bar, spring-pressed telescoping shells adapted to have pivotal connection with the truck bolster of a car, spring-pressed plungers within said shells, and rods connecting the plungers with the ends of said guiding 80 bar.

12. An automatic apparatus for regulating the valves in fluid pressure train pipes 85 comprising a boxing with recesses in the inner faces thereof, a train pipe valve having a stem projecting therefrom, intermeshing gear wheels, one of which is fitted to said stem, an adjustable table supporting said 90 gear wheels, rack bars movable within the recesses in the walls of the boxing, rollers underneath the rack bar, tracks formed in the bottoms of said recesses upon which said rollers rest, buffers mounted within the 95 rack bars, said rack bars having shank portions with elongated openings therein the lower walls of said openings having slots therein, a carriage having flanged wheels, the lower of which are adapted to ride upon the lower marginal edges of said openings and the upper wheels engaging the upper marginal edges of said openings, angle locking levers pivotally mounted in slots in the bottoms of the openings, a hook projecting 100 from each lever, spring-pressed catches mounted in recesses in the tracks and engaged by said hooks, an apertured partition in said boxing, a cylinder upon the carriage movable through said partition, a spring 105 interposed between the latter and one end of the carriage, a spring-pressed pipe mounted within said cylinder and having connection with said valve, a yoke mounted upon said pipe, a guiding bar pivotally connected to the yoke, a coupler upon the guide bar, and means attached to the guiding bar for connection with the truck bolster of a car.

115 13. An automatic apparatus for regulating the valves in fluid pressure train pipes 120 comprising a boxing with recesses in the inner faces thereof, a train pipe valve having a stem projecting therefrom, intermeshing gear wheels, one of which is fitted to said stem, an adjustable table supporting said gear wheels, rack bars movable within the recesses in the walls of the boxing, rollers underneath the rack bar, tracks formed in the bottoms of said recesses upon which said rollers rest, buffers mounted within the rack bars, said rack bars having shank portions with elongated openings therein the lower walls of said openings having slots therein,

125

comprising a boxing with recesses in the inner faces thereof, a train pipe valve having a stem projecting therefrom, intermeshing gear wheels, one of which is fitted to said stem, an adjustable table supporting said gear wheels, rack bars movable within the recesses in the walls of the boxing, rollers underneath the rack bars, tracks formed in the bottoms of said recesses upon which said rollers rest, buffers mounted within the rack bars, said rack bars having shank portions with elongated portions therein the lower walls of said openings having slots therein, a carriage having flanged wheels, the lower of which are adapted to ride upon the lower marginal edges of said openings and the upper wheels engaging the upper marginal edges of said openings, angle locking levers pivotally mounted in slots in the bottoms of the openings, a hook projecting from each lever, spring-pressed catches mounted in recesses in the tracks and engaged by said hooks, an apertured partition in said boxing, a cylinder upon the carriage movable through said partition, a spring interposed between the latter and one end of the carriage, a spring-pressed pipe mounted within said cylinder and having connection with said valve, a yoke connected to the pipe, rods connecting the arms of said yoke with the opposite end of the pipe and guided in apertures in said partition, a guiding bar fastened to the yoke, attachments to the yoke for attachment to the truck bolster of a car, a coupler head pivoted to the guiding bar, a forwardly extending projection upon the guiding bar, a spring-pressed tubular shell mounted upon said projection, and a plunger rod mounted within said tubular shell upon the projection and having connection with said coupler head.

15. An automatic apparatus for regulating the valves in fluid pressure train pipes comprising a boxing with recesses in the inner faces thereof, a train pipe valve having a stem projecting therefrom, intermeshing gear wheels, one of which is fitted to said stem, an adjustable table supporting said gear wheels, rack bars movable within the recesses in the walls of the boxing, rollers underneath the rack bars, tracks formed in the bottoms of said recesses upon which said rollers rest, buffers mounted within the rack bars, said rack bars having shank portions with elongated openings therein the lower walls of said openings having slots therein, a carriage having flanged wheels, the lower of which are adapted to ride upon the lower marginal edges of said openings, angle locking levers pivotally mounted in slots in the bottoms of the openings, a hook projecting from each lever, spring-pressed catches mounted in recesses in the tracks and engaged by said hooks, an apertured partition in said boxing, a cylinder upon the carriage movable through said partition, a spring interposed between the latter and one end of the carriage, a spring-pressed pipe mounted within said cylinder and having connection with said valve, a yoke connected to the pipe, rods connecting the arms of said yoke with the opposite end of the pipe and guided in apertures in said partition, a guiding bar fastened to the yoke, attachments to the yoke for attachment to the truck bolster of a car, a coupler head pivoted to the guiding bar, a forwardly extending projection upon the guiding bar, a spring-pressed tubular shell mounted upon said projection, and a plunger rod mounted within said tubular shell upon the projection and having connection with said coupler head.

15. An automatic apparatus for regulating the valves in fluid pressure train pipes comprising a boxing with recesses in the inner faces thereof, a train pipe valve having a stem projecting therefrom, intermeshing gear wheels, one of which is fitted to said stem, an adjustable table supporting said gear wheels, rack bars movable within the recesses in the walls of the boxing, rollers underneath the rack bars, tracks formed in the bottoms of said recesses upon which said rollers rest, buffers mounted within the rack bars, said rack bars having shank portions with elongated openings therein the lower walls of said openings having slots therein, a carriage having flanged wheels, the lower of which are adapted to ride upon the lower marginal edges of said openings, angle locking levers pivotally mounted in slots in the bottoms of the openings, a hook projecting from each lever, spring-pressed catches mounted in recesses in the tracks and engaged by said hooks, an apertured partition in said boxing, a cylinder upon the carriage movable through said partition, a spring interposed between the latter and one end of the carriage, a spring-pressed pipe mounted within said cylinder and having connection with said valve, a yoke connected to the pipe, rods connecting the arms of said yoke with the opposite end of the pipe and guided in apertures in said partition, a guiding bar fastened to the yoke, attachments to the yoke for attachment to the truck bolster of a car, a coupler head pivoted to the guiding bar, a forwardly extending projection upon the guiding bar, a spring-pressed tubular shell mounted upon said projection, and a plunger rod mounted within said tubular shell upon the projection and having connection with said coupler head.

14. An automatic apparatus for regulating the valves in fluid pressure train pipes comprising a boxing with recesses in the inner faces thereof, a train pipe valve having a stem projecting therefrom, intermeshing gear wheels, one of which is fitted to said stem, an adjustable table supporting said gear wheels, rack bars movable within the recesses in the walls of the boxing, rollers underneath the rack bars, tracks formed in the bottoms of said recesses upon which said rollers rest, buffers mounted within the rack bars, said rack bars having shank portions with elongated openings therein the lower walls of said openings having slots therein, a carriage having flanged wheels, the lower of which are adapted to ride upon the lower marginal edges of said openings, angle locking levers pivotally mounted in slots in the bottoms of the openings, a hook projecting from each lever, spring-pressed catches mounted in recesses in the tracks and engaged by said hooks, an apertured partition in said boxing, a cylinder upon the carriage movable through said partition, a spring interposed between the latter and one end of the carriage, a spring-pressed pipe mounted within said cylinder and having connection with said valve, a yoke connected to the pipe, rods connecting the arms of said yoke with the opposite end of the pipe and guided in apertures in said partition, a guiding bar fastened to the yoke, attachments to the yoke for attachment to the truck bolster of a car, a coupler head pivoted to the guiding bar, a forwardly extending projection upon the guiding bar, a spring-pressed tubular shell mounted upon said projection, and a plunger rod mounted within said tubular shell upon the projection and having connection with said coupler head.

otal connections with said bar and having sliding movements within said shells mounted upon said tubes, a pivotal forked lever having upwardly turned arms which are 5 forked for engagement with the ends of said shells upon the tubes to hold the carriage in a position to lock the valve open, and a bail-shaped member pivotally mounted upon

the boxing and positioned underneath the shank portion of said forked lever. 10

In testimony whereof I hereunto affix my signature in presence of two witnesses.

HOWARD S. KIMMEL.
